UNITED STATES PATENT OFFICE.

LILBURN HOWARD VAN BRIGGLE, OF INDIANAPOLIS, INDIANA.

DESIGN FOR A CARBURETER.

54,706.

Specification for Design.

Patented Mar. 9, 1920.

Application filed December 4, 1916. Serial No. 135,094. Term of patent 14 years.

To all whom it may concern:

Be it known that I, LILBURN HOWARD VAN BRIGGLE, a citizen of the United States, residing at Indianapolis, in the county of Marion and State of Indiana, have invented a new, original, and ornamental Design for Carbureters, of which the following is a specification, reference being had to the accompanying drawing, forming part thereof.

The single figure of the drawing is a per-

spective view of a carbureter, showing my new design.

I claim:

The ornamental design for a carbureter, as shown.

In witness whereof, I have hereunto set my hand at Indianapolis, Indiana, this 17th day of October, A. D. one thousand nine hundred and sixteen.
